United States Patent Office

Des. 176,951

Patented Feb. 21, 1956

176,951

NECKLACE OR THE LIKE

Adolph Katz, Providence, R. I., assignor to Coro, Inc.,
New York, N. Y., a corporation of New York

Application September 9, 1955, Serial No. 37,854

Term of patent 7 years

(Cl. D45—16)

Fig. 1

Fig. 2

Fig. 1 is a plan view of a necklace or the like showing my new design.

Fig. 2 is an edge view of the pendant portion.

The dominant feature of my design resides in the portion shown in solid lines.

I claim:

The ornamental design for a necklace or the like, substantially as shown and described.
